LOCKING DEVICE FOR DOORS AND THE
LIKE

Abraham Pinson, Brooklyn, N. Y.

Application October 31, 1936, Serial No. 108,501

10 Claims. (Cl. 292—37)

The present invention relates to locking devices for use in connection with doors or the like, and more particularly to locking means adapted for doors such as are generally used 5 on gates, cells, building entrances, safes and vaults.

One of the objects of the present invention is to incorporate in a door, locking means of improved construction for securing the door in 10 closing position with the door frame. Another object of the invention is to provide improved locking means for doors which will facilitate the locking and unlocking of the doors. Another object of the invention is to provide a locking 15 device for doors which operates to lock the door to the frame at opposite sides thereof simultaneously, and which serves to unlock the door in a similar manner. A further object of the invention is to provide a locking device for the purposes aforesaid, which is simple in construction 20 and practical in use. Other objects and advantages of the present invention will in part be pointed out hereinafter and will in part be apparent to those skilled in the art to which the 25 invention relates.

With the above and other objects in view, the present invention consists of the novel construction, combination and arrangement of parts hereinafter more fully described and illustrated 30 in the accompanying drawings wherein there is shown a preferred embodiment of the invention.

In the accompanying drawings forming an integral part of this specification,

Fig. 1 is a plan view of a pair of swinging doors and door frame incorporating the invention;

Fig. 2 is a vertical sectional view of the locking devices constructed in accordance with the principle of the present invention, showing one in locked position and the other in unlocked position;

Fig. 3 is an enlarged cross sectional view on the line 3—3 of Fig. 2;

Fig. 4 is a fragmentary plan view of one of the locking devices;

Fig. 5 is a perspective view of one of the rotary sleeve elements of the device; and

Fig. 6 is a perspective view of a portion of the door frame showing a recess for receiving the locking members.

Referring now to the drawings wherein like reference characters indicate corresponding parts throughout the several views, Fig. 2 shows by way of illustration a door frame 10 of substantially rectangular shape, to the sides of which are hinged a pair of swinging doors 11. The locking

devices 12 are incorporated within the inner marginal portions of the doors 11, and are adapted to lock the doors to the top and bottom of the door frame 10.

As illustrated in Figs. 2, 3 and 4, the locking device consists of a longitudinal tubular casing 14, which is preferably constructed integral with the door. The casing 14 is provided with two annular flanges 15 and 16, which are in spaced relation, and with two oppositely disposed longitudinal slots 17, which are arranged between the two flanges. Embracing the casing 14 and positioned between the two flanges 15 and 16 is a sleeve 18, which is adapted to rotate relative to the casing 14, and is actuated by means of a handle 19. The rotary sleeve 18 consists of two longitudinal sections which are joined together by means of bolts 20, which pass through the ears 21. If desired, the two sections of the sleeve 18 may be welded together. Each section 20 of the sleeve 18 is provided on the inner surface with a spiral groove 22 in the upper portion thereof and an oppositely disposed spiral groove 23 in the lower portion thereof, as illustrated in Fig. 6. It will be apparent, that when the two sections of the sleeve 18 are joined together, there is provided a pair of oppositely convoluted, spiral grooves 22 in the upper portion of the sleeve 18, and a similar pair of oppositely convoluted spiral grooves 23 in the lower portion of the sleeve 18. The function of the spiral grooves and the purpose of their arrangement will be brought out hereinafter.

Carried within the tubular casing 14 are two bolts 24 and 25. The bolt 24 is adapted to slide vertically within the upper portion of the casing 14 and the bolt 25 is adapted to slide vertically within the lower portion of the casing. The bolt 24 is provided at its lower end with a cross pin 26, the ends of which are adapted to project through the longitudinal slots 17 in the casing 14 and to engage the oppositely convoluted spiral grooves 22 in the sleeve 18. Likewise, the bolt 25 is provided at its upper end with a cross pin 27, the ends of which are adapted to project through the longitudinal slots 17 in the casing 14 and to engage the oppositely convoluted spiral grooves 23 in the sleeve 18. The bolts may be constructed of solid material or they may be tubular in construction with solid tips 28 fitted into the ends as shown in Fig. 2.

Recesses may be provided in the top and bottom of the door frame 10 to receive the bolts 24 and 25 respectively.

In Fig. 5, there is shown a portion of the top

of the door frame 10 having a depending flange 29 to provide a recess 30 for receiving the bolts 24. The flange 29 is preferably provided with an apron 31 which serves as a back stop for the doors in closed position.

When the door 11 is in unlocked condition, the handle 19 of the rotary sleeve 18 is situated to one side, away from the inner edge of the door. In this condition, the bolts 24 and 25 are wholly contained within the casing 14. The cross pin 26 is then at the lowermost points within the oppositely convoluted grooves 22 and the cross pin 27 is at the uppermost points within the oppositely convoluted grooves 23. Both cross pins 26 and 27 are situated intermediate the ends of the longitudinal slots 17. When it is desired to lock the door, the handle 19 is swung to the opposite side so as to rotate the sleeve 18 relative to the casing 14. By this action, the cross pin 26 is guided by the spiral grooves 22, so as to move upwardly within the slots 17, thereby ejecting the bolt 24 from the casing 14 and causing it to enter into locking engagement with the recess at the top of the door frame. Simultaneously the cross pin 27 is guided by the spiral grooves 23 so as to move downwardly within the slots 17, thereby ejecting the bolt 25 from the casing 14 and causing it to enter into locking engagement with a recess in the bottom of the door frame. In order to unlock the door, the sleeve 18 is rotated back to its original position by means of the handle 19. The bolts 24 and 25 are thus drawn into the casing 14 and out of locking engagement with the door frame. It will thus be apparent that the locking device operates to simultaneously lock the door to the top and bottom of the door frame with but a single movement of the handle 19 and to unlock the door in a similar manner. The length and pitch of the spiral grooves in the sleeve 18 are designed to give the required vertical displacement to the bolts 24 and 25. The ends of the spiral grooves are preferably cut horizontally as shown at 32, so as to provide shoulders upon which the cross pins may be retained against slipping out of position.

When the doors are in locked relation with the door frame, the locking devices may be secured against unlocking by means of a latch 13, which is adapted to engage the lugs 33 on the 50 rotary sleeves 18 and thus hold them against counterrotation.

Although the invention is essentially as described hereinabove and as shown in the drawings, it is desired to be understood that the 55 invention is not limited to the specific embodiment thereof herein shown and described for the purpose of illustration, but that numerous changes may be made in the details of construction which will fall within the scope of the invention as defined in the appended claims.

Having thus described and illustrated the invention, what I claim as new and desire to secure by Letters Patent is:

1. In a door or the like, locking means, comprising a tubular casing integral with the door and having a longitudinal slot therein, a rotary sleeve embracing the casing, said sleeve being provided internally with a spiral groove, a bolt 65 slideable longitudinally within the casing, a pin on said bolt projecting through the slot in the casing and engaging the spiral groove in the sleeve, and means for rotating the sleeve relative to the casing whereby the bolt is reciprocated within the casing.

2. In a door or the like, locking means, com-

prising a tubular casing integral with the door and having oppositely disposed longitudinal slots therein, a rotary sleeve embracing the casing, said sleeve being provided internally with oppositely convoluted spiral grooves, a bolt slideable longitudinally within the casing, a cross pin on said bolt projecting through the slots in the casing and engaging the oppositely convoluted spiral grooves in the sleeve and means for rotating the sleeve relative to the casing whereby the bolt is reciprocated within the casing.

3. In a door or the like, locking means, comprising a tubular casing integral with the door and having a longitudinal slot therein, a rotary sleeve embracing the casing, said sleeve being 15 provided internally with a spiral groove in one portion thereof and an oppositely disposed spiral groove in the other portion thereof, a bolt slideable longitudinally within one portion of the casing, and another bolt slideable longitudinally within the other portion of the casing, each bolt having a pin 20 projecting through the slot in the casing and engaging the corresponding spiral groove in the sleeve, and means for rotating the sleeve relative to the casing whereby the bolts are simultaneously reciprocated within the casing.

4. In a door or the like, locking means, comprising a tubular casing integral with the door and having oppositely disposed longitudinal slots therein, a rotary sleeve embracing the casing, 30 said sleeve being provided internally with a pair of oppositely convoluted spiral grooves in one portion thereof, and an oppositely disposed pair of oppositely convoluted spiral grooves in the other portion thereof, a bolt slideable longitudinally within one portion of the casing, and another bolt slideable longitudinally within the other portion of the casing, each bolt having a cross pin 35 projecting through the slots in the casing and engaging the corresponding pair of oppositely convoluted spiral grooves in the sleeve, and means for rotating the sleeve relative to the casing whereby the bolts are simultaneously reciprocated within the casing.

5. In a door or the like, locking means, comprising a tubular casing integral with the door and having two oppositely disposed longitudinal slots therein, a rotary sleeve embracing the casing, said sleeve being provided internally with a pair of oppositely convoluted spiral grooves 50 in one portion thereof, and an oppositely disposed pair of oppositely convoluted spiral grooves in the other portion thereof, a bolt slideable longitudinally through one end of the casing and another bolt slideable longitudinally 55 through the other end of the casing, the inner end of each bolt having a cross pin projecting through the slots in the casing and engaging the corresponding pair of oppositely convoluted spiral grooves in the sleeve and means for rotating the sleeve relative to the casing whereby the bolts are simultaneously reciprocated within the casing.

6. In a door or the like, locking means, comprising a tubular casing integral with the door and having two annular flanges and two oppositely disposed longitudinal slots therein arranged between said flanges, a rotary sleeve embracing the casing and positioned between the said flanges, said sleeve being provided internally 70 with a pair of oppositely convoluted spiral grooves in one portion thereof and an oppositely disposed pair of oppositely convoluted spiral grooves in the other portion thereof, a bolt slideable longitudinally through one end of 75

- the casing and another bolt slidable longitudinally through the other end of the casing, the inner end of each bolt having a cross pin projecting through the slots in the casing and engaging the corresponding pair of oppositely convoluted spiral grooves in the sleeve, and a handle on the sleeve for rotating it relative to the casing, whereby the bolts are simultaneously reciprocated for engagement with the door frame.
7. A pair of doors, each having a tubular casing integral therewith along the inner marginal portion thereof, each casing having two oppositely disposed longitudinal slots therein, a rotary sleeve embracing each casing, each of said sleeves being provided internally with a pair of oppositely convoluted spiral grooves in one portion thereof and an oppositely disposed pair of oppositely convoluted spiral grooves in the other portion thereof, a pair of bolts slidable longitudinally through respective ends of each casing, the inner end of each bolt having a cross pin projecting through the slots in the casing and engaging the corresponding pair of oppositely convoluted spiral grooves in the sleeve, each sleeve having a handle for rotating it relative to the casing which it embraces, whereby the bolts in the casing are simultaneously reciprocated for engagement with the door frame, and means for locking the two sleeves together in closed position.
8. A locking device for doors or the like comprising a tubular casing having oppositely disposed longitudinal slots therein, a bolt slidable longitudinally within the casing, said bolt having a cross pin projecting through the slots in the casing, a rotary sleeve embracing the cas-

ing, said sleeve being provided internally with oppositely convoluted spiral grooves for engagement with the cross pin of the bolt, whereby upon rotation of the sleeve the bolt is reciprocated within the casing.

9. A locking device for doors or the like comprising a tubular casing having oppositely disposed longitudinal slots therein, a pair of bolts each slidable longitudinally within the casing, the inner end of each bolt having a cross pin projecting through the slots in the casing, a rotary sleeve embracing the casing, said sleeve being provided internally with a pair of oppositely convoluted spiral grooves in one portion thereof, and an oppositely disposed pair of oppositely convoluted grooves in the other portion thereof, for respective engagement with the cross pins of the bolts, whereby upon rotation of the sleeve the bolts are simultaneously reciprocated within the casing.

10. A locking device for doors or the like comprising a tubular casing having two oppositely disposed longitudinal slots therein, a pair of bolts each slidable longitudinally within the casing, the inner end of each bolt having a cross pin projecting through the slots in the casing, a rotary sleeve embracing the casing, said sleeve comprising two longitudinal segments joined together, each segment being provided internally with a pair of longitudinally spaced oppositely convoluted spiral grooves for respective engagement with the cross pins of the bolts, whereby upon rotation of the sleeve the bolts are reciprocated within the casing.

ABRAHAM PINSON. 35
